INFLATABLE CUSHION PAD FOR A GOLF BAG SHOULDER STRAP OR THE LIKE

Bill N. Lovelace and Frank A. Pritchard, both of 2215 Bennett, Wichita, Kans. 67213

Filed Feb. 12, 1973, Ser. No. 331,354

Term of patent 14 years

Int. Cl. D21—02
U.S. Cl. D34—5 GB

— 1 — 2 — 3 —

FIG. 1 is a plan view of the cushioned face of an inflatable cushion pad for a golf bag shoulder strap or the like embodying the design of our invention;

FIG. 2 is a side elevation view of same;

FIG. 3 is a plan view of the face opposite to that of FIG. 1 which is the face that in use contacts a person's shoulder or the like; and

FIGS. 4 and 5 are the end elevation views of same.

We claim:

The ornamental design for an inflatable cushion pad for a golf bag shoulder strap or the like, substantially as shown and described.
